COMBINATION STOVEPIPE T-FITTING
AND CLOSURE

Louis K. Weinstein, Bronx, N. Y.

Application June 27, 1944, Serial No. 542,407

3 Claims. (Cl. 285—213)

1

This invention relates to pipe or flue conduits, and has particular reference to a combination elbow or T-fitting and closure, the utility of which is best exemplified in a stove pipe.

One object of the invention is the provision of a device of the character described having improved means for eliminating the outer angle of a pipe and substituting therefor a curved surface preferably without necessitating any change in the structure of the elbow.

Another object of the invention is to provide a device as set forth having improved means for eliminating or reducing excessive eddy currents in an angular conduit, and for avoiding the large deposit of soot that usually occurs in a stove pipe or the like, especially at the pocket adjacent to the cleanout plug or closure.

Another object of the invention is the provision of a device of the type mentioned having a projection or handle whereby the curved surface portion is not only placed in proper position but also tensioned in an angular manner to afford a relatively tight or a securely locked wall or closure.

Another object of the invention is the provision of a device of the class alluded to having improved means whereby an element is movably disposed in a T-fitting to change it into an elbow fitting.

Another object of the invention is to furnish a device of the nature described having improved means whereby the main curved wall portion of an elbow is so arranged as to constitute a cleaning or scraping element for at least part of the element and the conduit therebeyond.

Another object of the invention is to construct a device of the character described having improved means including a stream lining curved element removably positioned at the inner angle or relatively sharp apex of an elbow to reduce eddying of the fluid therein and to permit unobstructed cleaning of the elbow when necessary; a supplemental object is to associate such element with any closure, curved wall, or scraper element for a T-fitting whereby the elements may perform their individual functions without interference with each other, or whereby the elements may conjointly function in stationary or in moving condition or both to thus realize their intended functions in a highly efficient manner.

Other objects and advantages of the invention will become apparent as the specification proceeds.

With the aforesaid objects in view, the invention comprises the novel features, combinations and arrangements of parts hereinafter described

2

in their preferred embodiments, pointed out in the subjoined claims, and illustrated in the annexed drawing, wherein like parts are designated by the same reference characters throughout the several views.

In the drawing:

Figure 1 is a fragmentary view in vertical section showing a conduit or stove pipe embodying the invention.

Fig. 2 is a view in elevation looking at the left of Fig. 1.

Fig. 3 is a plan view of a blank for the curved wall element of Fig. 1.

Fig. 4 is a view similar to that of Fig. 1, showing a modification according to the invention.

Fig. 5 is an end view of Fig. 4.

The advantages of the invention as here outlined are best realized when all of its features and instrumentalities are combined but, useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes a device embodying the invention. The same 30 may be denoted a conduit, or an elbow or T-fitting, the fitting 11 having at least its vertical arm 12 and one of its horizontal arms 13 sufficiently elongated to form straight pipe portions, another of the horizontal arms 14 being a relatively short arm which is provided for the closure. When used as a stove pipe, the arm 12 is connected to a stove and the arm 11 to the flue. In the exemplification shown, the structure is made of sheet metal, the arm 12 being suitably joined into the horizontal section along a line 15.

Heretofore, the branch 14 has been generally closed by a plug-like removable element to facilitate cleaning. In a stove pipe, the relatively sharp apex as at 16 and the pocket 17 afforded by the 45 branch 14 constituted about the worst possible flow condition, producing a great deal of eddying of the gases, and resulting in a settling out of soot which deposited in the pocket 17 and in the branch 13. It will be perceived that the stream of gases from branch 12 hurled itself at least in part against the opposing top wall of the device 10 producing many eddy currents in different directions, the effect of such eddies being the same as though the device 10 were constricted at the elbow. While means have been devised hereto-

fore to facilitate cleaning of the device 10, no means to my knowledge has been discovered heretofore to get at the root of the difficulty by reducing the eddy currents and the deposit of soot, in order to place less dependence on cleaning which is often overlooked or forgotten. To produce a properly curved sheet metal T-fitting is expensive, and even so the pocket as at 17 remained. By the present invention, a new and novel adjunct 18 is provided for the conduit, which is about as cheap and may be even cheaper than the ordinary plug-like closure, while performing the several additional functions herein described.

That adjunct comprises a curved wall 19, which may have a supporting foot or extension 20, the wall being constructed of an ovoid blank such as shown at 21. This blank need not be caved into dish shaped form but may be curved only about its shorter axis, to produce the wall 19 to snugly fit in the conduit at an angle of about 45 degrees, the extension 22 of the blank being cut for bending on a straight line, or being bent on a curved line 23 as with a die, to produce the support 20. The latter assures that the wall 19 will not tend to drop into the branch 12. Secured to the wall 19 as by being spot welded or riveted thereto is a projection or handle 24 in the branch 14, the handle having a hand grip portion 25 located above the bottom of the branch 14, whereby the element 24 is a cantilever weighted at its outer end to tend to tilt the wall 19 clockwise into tight engagement with the interior surface of the conduit. A more positive pressure for this purpose may be obtained by extending the portion 25 upward into contact with the top wall of the branch 14, as at the portion 26, whereby the arm or handle 24 exerts a definite pressure tending to turn the wall 19 clockwise to snugly and frictionally engage the conduit wall. Since the interior of the conduit is under suction due to chimney draft, a slight leakage is immaterial, yet with oil burners, for instance, a momentary pressure occurs, due to the explosive burning of the fuel especially at the instant of ignition, and it is not desirable that soot particles be blown out of the conduit. The frictional securing between the conduit or wall of the T-fitting at 19 and at 26 will prevent longitudinal shifting of the wall due to momentary gaseous pressure. While the portion 26 could be secured to a wall of the fitting as by a bolt or screw, in order to provide a minimum of manipulation it is preferred to use merely a stop or indicator to limit insertion of the wall 19 for precise alignment with the branch 12. Thus a screw may be removably connected in the portion 26 with its head adapted to abut an edge 28 of the conduit or branch 14.

If desired the device 18 may be used to clean the conduit or fitting at the section 13. For this purpose the screw 27 may be removed, the handle gripped at 25, and then the wall 19 may be further inserted and rotated to scrape off and clean out soot. The wall 19 may be used as a scoop to collect soot, and hence may have a long slope, and may be further elongated at its leading edge 29.

In Figs. 4 and 5 is shown a modified device 30 according to the invention, the same being in all respects like the device 18 except as described. Associated with the wall 31 is a curved, sloping portion 32 for streamlining the fitting at its inner angle or apex 16; hence the wall 31 has a shorter radius of curvature than the wall 19,

the center being at 16. This portion 32 is curved at 33 into register with the adjacent wall of the branch 12, and slopes forward and downward at 34 like a Venturi wall. The portion 32 may also be curved about the axis of branch 13, but sufficient benefit is obtained by making it like a chord as in Fig. 5. This portion 32 is rigidly connected to the wall 31 by any suitable means, positioned to effect little disturbance of the flowing gases, and it may consist in a rod 35, which, although centrally located, is quite thin. This rod may form an integral extension of the handle 36, if desired, with spot welding at the wall 31 and riveting or spot welding at the portion 32. Accordingly, the elements 31, 32 are slidable as a unit by manipulation of the handle 36. Instead of the screw 27, a device like a wingnut 37 may be rotatably riveted to the handle portion 38 at 39. This nut or head 37 may have an eccentric portion 40 rotatable into a position as in Fig. 4 to about an edge of branch 14, or into a position in which it clears said edge so that the device 30 may be slid in and out without obstruction, to scrape out soot. As in the device 19, the wall 31 may be sufficiently elongated at its leading edge to form a scoop for the soot. In tending to tilt the wall 31 clockwise, the position of the element 32 need not be affected because such tilting movement may be extremely small or quite insignificant. If preferred, both of the members 35 and 36 may be resilient for effectuating their intended purposes and the edge 41 of the element 32 may be regarded as beveled to facilitate its sliding past the edge 16, or the latter may be beveled for that purpose.

I claim:

1. A combination chimney elbow and closure including a T-fitting the three branches of which are at right angles to each other, a sheet metal closure wall member in one of two aligned branches confronting the third branch, the wall member being sufficiently thin so that its edge remote from the third branch constitutes a scraper, said wall member being inclined to confront the third branch, said wall member having a normal position in which it constitutes a deflector, said wall member being lineally slidably along the fitting and rotatable to scrape clean adjacent portions of the fitting, and a rod connected to the wall member generally centrally thereof and lying in the branch containing the wall member, said rod having a laterally bent portion constituting a handle for moving the wall member, the handle having an end section slidably engaging an inner surface of the fitting whereby the wall member is maintained in said inclined position.

2. A combination chimney elbow and closure according to claim 1 wherein a stop portion is mounted on said end section of the handle for releasably engaging an end of the branch containing the handle to thus set the wall member in said normal position.

3. A combination chimney elbow and closure including a T-fitting having a main horizontal passage and a secondary vertical passage at right angles thereto, a movable wall deflector and closure member in the horizontal passage disposed in a branch of the fitting and sloping to confront the secondary passage to stream-line the fitting, said wall member being lineally slidably along the main passage past the secondary passage to scrape clean the portion of the fitting into which the secondary passage discharges the furnace exhaust, said wall having a handle

portion sufficiently elongated for corresponding movement into the main passage, and an eccentric element rotatably mounted on the handle portion for movement to laterally engage and disengage the first mentioned branch to respectively set the wall member in confronting relation to the secondary passage and to move with the handle portion into the main passage as the wall member moves past the secondary passage.
